UNITED STATES PATENT OFFICE.

DANIEL W. CAMPBELL, OF WEST TROY, NEW YORK.

STREET-PAVEMENT.

SPECIFICATION forming part of Letters Patent No. 429,303, dated June 3, 1890.

Application filed March 18, 1889. Serial No. 303,688. (No model.)

To all whom it may concern.

Be it known that I, DANIEL W. CAMPBELL, a resident of West Troy, in the county of Albany and State of New York, have invented 5 certain new and useful Improvements in Street-Pavements; and I do hereby declare that the following is a full, clear, and exact description of the invention, that will enable others skilled in the art to which it appertains 10 to make and use the same, reference being had to the accompanying drawings, and to the letters of reference marked thereon, which form a part of this specification.

Similar letters refer to similar parts in the 15 several figures therein.

My invention relates to improvements in street-pavements; and it consists of the novel construction and combination of parts hereinafter described, and pointed out in the 20 claim.

Figure 1 of the drawings is a vertical transverse section of my improved pavement laid upon a street-surface, having the middle part broken away. Fig. 2 is a vertical longitudinal 25 section of the pavement on an enlarged scale. Figs. 3 and 4 are respectively perspective views of a block-supporting strip and paving-block on a still larger scale.

The blocks A are made alike and provided 30 on two opposite sides with offsets, forming the oppositely-facing abutments or ledges B'.

The strips C are made of a thickness equal to the depth of the offsets in the blocks and of a width equal to the distance between the 35 ledges on the contiguous sides of two blocks when placed in position for use. The blocks are preferably made of brick or stone and the strips of wood or other flexible yielding material.

40 The method of forming the pavement from such blocks and strips is as follows: A row of blocks is laid upon the surface of the street, extending transversely of the same, from the curbstone D on one side of the street to the stone

45 D' on the opposite side, with all the ledges B' located on one side of the row—for example, on the front side, as shown in Fig. 1, and on the right, as shown in Fig. 2—and all the ledges B on the opposite side. A strip C is then laid 50 with its lower edge resting upon the ledges B', as shown in Figs. 1 and 2. Another row

of blocks is then laid parallel to the first and with the ledges B resting upon the upper edge of the strip, as shown in Fig. 2, and so on, a strip and a row of blocks, until a pavement 55 is formed of the desired length.

Such a form of construction presents a yielding flexible pavement that will not easily get out of order, and will not communicate so sharp vibrations either to the atmosphere or 60 to the ground as brick or stone pavements made of blocks supported by the ground without any intervening yielding material.

By extending the interposed strips transversely across the street there is little or no 65 danger of forming longitudinal ruts or depressions in the street by the more frequent use of certain longitudinal rows of blocks, such as would depress them if unsustained by the strips below the level of the other rows. 70

I am aware that street-pavements have been made from blocks severally grooved on their opposite sides and laid in rows, the contiguous rows being united by dovetailed strips inserted in such grooves, one half of each 75 strip in the groove of one row and the other half of the strip in the groove of a contiguous row, whereby a shear movement of the rows of blocks relatively to each other would split the strips and shear off one half from the 80 other half, leaving the rows of blocks wholly unconnected with each other.

My improved pavement differs from such form of construction in that the abutting projections on the contiguous sides of the several 85 rows of blocks lap each other and wholly inclose the upper and lower edges of the interposed strips, the vertical sides of the strips being inclosed and supported by the vertical sides of the blocks, whereby a shear movement of 90 the rows of blocks would be limited to the compressibility of the strips, and could not in any case be sufficient to destroy the function of the strips, thereby affording a durable and comparatively noiseless pavement. 95

What I claim as new, and desire to secure by Letters Patent, is—

In a street-pavement, a plurality of rows of blocks, offsetting abutments on the opposite vertical sides of the individual rows, those on 100 one side of a row being near the upper ends of the blocks and those on the opposite side

near the lower ends of the blocks and in the same vertical plane with the upper-end abutments on the adjoining side of a contiguous row, in combination with a plurality of strips 5 formed of some yielding substance, the individual strips being inclosed by two contiguous rows of blocks, the upper edges of the strips being wholly inclosed by the upper-end abutments and the lower edges of the

strips being wholly inclosed by the lower-end abutments, substantially as described.

In testimony whereof I have hereunto set my hand this 2d day of February, 1889.

DANIEL W. CAMPBELL.
